CARBURETOR

James G. Allen, Detroit, Mich., assignor to Bé-
dix Products Corporation, South Bend, Ind.,
a corporation of Indiana

Application April 20, 1935, Serial No. 17,434

6 Claims. (Cl. 261—41)

This invention relates to carburetors, and more particularly to a novel priming device adapted for use in conjunction with the choke valve of a carburetor, to supply a suitable charge of combustible mixture for starting the engine to which the carburetor is attached.

One important object of this invention is to provide a device wherein the choke valve may be positively closed, while a suitable charge of combustible mixture is furnished to the carburetor in accordance with suction existing in the carburetor to start and warm up the engine.

Another object of this invention is to provide a carburetor with a venturi communicating with the atmosphere at all times and operable to supply a rich charge of combustible mixture when the choke valve is closed.

A still further object of the invention is to provide a novel priming device adapted to withdraw liquid fuel from the fuel reservoir through a vented tube communicating with the most restricted section of a priming venturi communicating with the atmosphere and adapted to supply a rich fuel mixture to the engine when the choke valve is in the closed position.

Another object of this invention is to provide a priming venturi adapted to supply a combustible mixture to the carburetor when the choke valve is closed, but so designed and positioned as to become inoperative when the choke valve is opened to such a position as to subject the inner end of the venturi to substantially atmospheric pressure.

Other objects and advantages of this invention will be apparent from the following detailed description thereof together with the accompanying drawing, submitted for purposes of illustration only, and not intended to define the scope of the invention, reference being had for that purpose to the subjoined claims.

The drawing shows a carburetor having a vertical upper body section 10, and a lower body section 12. The lower body section 12 comprises a fuel reservoir 14 equipped with a fuel level regulating float 16, and a substantially horizontal air inlet passage 18. A choke shaft 20, rotatably mounted in the walls of the air inlet passage 18 is provided with a choke valve 22 adapted to be actuated either manually or automatically to variably control the amount of air admitted to an induction passage 24 formed in the lower body section 12 and the upper body section 10.

The upper body section 10 is provided with a manually controlled throttle valve 26 fixed to a

throttle shaft 28 rotatably mounted in the walls of the upper body section 10.

Liquid fuel is supplied from the fuel reservoir 14 through the passages 30 and 32 communicating with the main fuel discharge nozzle 34 positioned to discharge into the induction passage 24 at the most restricted section of a venturi 36, carried by the upper body section 10, and extending into the lower body section 12.

Fuel for idling purposes is provided through the passageway 38 communicating with the main fuel discharge nozzle 34 and extending to the passages 40 and 42 communicating with the induction passage 24 on either side of the throttle valve 26, when in the closed position. The quantity of fuel supplied for idling purposes is adjustably controlled by means of a manually operable valve member 44 provided with a spring 46 to prevent accidental rotation thereof.

A combustible mixture formed by the admixture of air admitted through the air inlet passage 18 beyond the choke valve 22 with fuel drawn from the main fuel discharge nozzle 34 is supplied to the induction passage 24 and is passed to the engine beyond the throttle valve 26 under the pumping action of the engine to which the carburetor is attached.

A priming venturi 48 is threaded or otherwise secured in the lower portion of the induction passage 24. Duct 50 extending into the fuel reservoir 14 communicates with the priming venturi 48 at the most restricted section (52) thereof. The duct 50 is provided with a vent 54 at the upper extremity thereof, adapted to vent the duct to avoid a syphoning action. The venturi 48 communicates with atmosphere at all times and projects into the induction passage at a suitable angle to provide an unobstructed passage of air admitted through the venturi, and fuel drawn through the duct 50, to the upper end of the induction passage, upon slight opening of the throttle valve 26. The upper end 56 of the venturi 48 is beveled, as shown, to be subject to the velocity pressure of the air entering through air inlet 18, so as to equalize the pressures at both ends of the venturi 48 when the choke valve 22 is open and the engine to which the carburetor is attached is being operated at high speed. This arrangement prevents the withdrawal of fuel from the fuel reservoir 14 through the duct 50 at all times except when the choke valve 22 is in the substantially closed position.

The operation of this device is as follows. When it is desired to start the engine, the choke valve 22 is moved to the closed position, whereupon the

induction passage 24 will be subjected to high suction and air will be drawn through the priming venturi 48. As air flows through this venturi a high suction is exerted at the restricted section 5 52, whereupon fuel is drawn from the fuel reservoir 14 through the duct 50 to mix with the air passing through the venturi, to provide a rich mixture to start the engine. When the engine has started, the choke valve 22 is moved toward 10 the open position, admitting an increasing flow of air through the air inlet passage 18, to destroy the suction exerted in the induction passage 24, thereby decreasing the flow of air through the priming venturi 48, whereupon the flow of 15 fuel through the duct 50 will be decreased. As the choke valve is moved further in the opening direction the pressure within the lower section of the induction passage 24 will approach atmospheric, whereupon the pressures at the inner 20 end 56 of the venturi 48 and at the outer end thereof will be substantially equalized, and the flow of fuel through the duct 50 will be interrupted. The vent 54, positioned in the duct 50 is operable to prevent fuel from syphoning 25 through the duct 50.

While the invention has been described with reference to a preferred embodiment, it is not intended that the invention should be limited to the features shown nor otherwise than by the 30 terms of the following claims.

I claim:

1. A carburetor having an induction passage, choke and throttle valves controlling the induction passage, a fuel reservoir, a fuel nozzle communicating with the fuel reservoir and adapted to discharge fuel into induction passage between the choke and throttle valves, idling fuel passages adapted to supply fuel to the induction passage posterior to the throttle when the throttle valve is closed, a priming venturi interconnecting the induction passage intermediate the choke and throttle valves with the atmosphere, means including a duct positioned at the most restricted section of the priming venturi to supply fuel thereto from the fuel reservoir when the choke valve is closed and the throttle valve is moved from the closed position, and a vent in the duct above the fuel level in the fuel reservoir to prevent fuel from flowing through the duct 50 except in the presence of strong suction in the induction passage.

2. An updraft carburetor having a vertically disposed induction passage, a horizontally disposed air inlet passage, a choke valve controlling the admission of air to the air inlet passage, a venturi positioned in the induction passage, a fuel reservoir, a fuel discharge nozzle communicating with the fuel reservoir and adapted to discharge into the induction passage at the most restricted section of the venturi, a throttle valve adapted to control the flow of combustible mixture through the induction passage, means including a priming venturi communicating with the atmosphere and discharging into the induction passage between the choke valve and its fuel nozzle, means including a duct to supply the priming venturi with fuel from the fuel reservoir, a vent in the duct to prevent the flow of fuel to the priming

venturi in the absence of high suction in the induction passage, said priming venturi being positioned in the induction passage at an appropriate angle to permit an unobstructed flow of combustible mixture through the induction passage when the throttle valve is moved from the closed position, and a fuel sump in the induction passage between the choke valve and the fuel nozzle adapted to collect excess fuel.

3. A carburetor having an induction passage, a choke valve controlling the admission of air to the induction passage, a venturi positioned in the induction passage, a fuel reservoir, a fuel discharge nozzle communicating with the fuel reservoir and adapted to discharge at the most restricted section of the venturi, a throttle valve adapted to control the flow of combustible mixture through the induction passage, means including a priming venturi communicating between the atmosphere and the induction passage, and means to supply the priming venturi with fuel from the fuel reservoir, the upper end of said priming venturi being beveled adjacent the choke valve to subject the priming venturi to atmospheric pressure upon slight opening movement of the choke valve to interrupt the flow of fluid therethrough.

4. In a carburetor, an induction passage, a throttle and a choke valve controlling the same, a constant level fuel chamber, and priming means including a restricted air inlet of venturi form discharging into the induction passage between the choke valve and the throttle, and a vented fuel duct extending from the fuel space in the fuel chamber to a point above the fuel level and discharging into the venturi at a point below the fuel level.

5. A carburetor having an induction passage, choke and throttle valves controlling the induction passage, a fuel reservoir, a fuel nozzle communicating with the fuel reservoir and adapted to discharge fuel into the induction passage between the choke and throttle valves, a generally vertically disposed priming venturi interconnecting the induction passage intermediate the choke valve and the fuel nozzle with the atmosphere, and means including a fuel duct positioned at the most restricted section of the priming venturi to supply fuel to the induction passage from the fuel reservoir when the choke valve is closed and the throttle valve is moved from the closed position, the priming venturi being so positioned that pressure on opposite ends thereof are substantially equalized when the choke valve is fully opened.

6. In a carburetor, an induction passage having a venturi therein, a throttle and a choke valve controlling said passage, a constant level fuel chamber, a main fuel nozzle connecting the fuel chamber and the venturi, and priming means including a restricted air inlet into the induction passage between the choke valve and the venturi, said air inlet being of venturi shape, and a fuel duct extending from the fuel space in the fuel chamber to a point above the level thereof and discharging in said air inlet, said fuel duct being provided with a vent above said fuel level.

JAMES G. ALLEN.
